UNITED STATES PATENT OFFICE.

GUY H. ELMORE, OF SWARTHMORE, PENNSYLVANIA, AND OSCAR H. BOHM, OF BIRMINGHAM, ALABAMA.

JIG.

1,102,574.

Specification of Letters Patent.

Patented July 7, 1914.

Application filed November 11, 1912. Serial No. 730,674.

To all whom it may concern:

Be it known that we, GUY H. ELMORE, a citizen of the United States, and resident of Swarthmore, in the county of Delaware and 5 State of Pennsylvania, and OSCAR H. BOHM, a citizen of the United States, and resident of Birmingham, in the county of Jefferson and State of Alabama, have invented certain new and useful Improvements in Jigs, 10 of which the following is a specification.

This invention relates to jigs for separating and classifying mineral substances according to their specific gravities, and the principal features of novelty reside in the 15 discharge mechanism for the heavier substances forming the strata near the jig screen. In the case of metalliferous ores these strata are the concentrates, while in jigs used for washing coals these strata are 20 the slate, bone and similar refuse.

While capable of other use, our invention finds perhaps its greatest utility in jigs for washing coarse coals and the like.

The object of the present invention is to 25 provide a discharge mechanism for jigs which will discharge the solid material but which will prevent the free outflow of water through the discharge.

The invention attains its greatest usefulness in discharging the coarser ores and coal, the basic principle of the invention being the 30 use of a pocketed discharge valve having a restricted entrance aperture, which operates to prevent the complete filling of the pockets 35 of the valve, thus allowing the contained solid material to fall clear of the sealing face of the valve in order to prevent clogging. Other advantages of the invention will be apparent to those skilled in the art.

40 The present improvements will now be described in connection with the accompanying drawings, wherein:—

Figure 1 is a vertical section through the 45 discharge mechanism of a jig showing our improvements applied; Fig. 2 is a section on the line II—II of Fig. 1; and Fig. 3 is a perspective view of the rotary valve member forming a part of the discharge mechanism.

We illustrate only the discharge mechanism which is capable of application to a wide range of jigs and for example is readily applicable to a jig of the general type illustrated in Patent No. 997,609, granted July 11, 1911 to Guy H. Elmore.

55 In the drawings, 1 represents the walls of

the jig tank which are extended at 2 to form an overhanging discharge pocket, closed along the end at 3 and open at the bottom at 4. Mounted in this overhanging portion is a metal tube 5, finished on its inner surface, 60 and provided with two opposite longitudinal ports or apertures 6 and 7 through which the discharged material is destined to pass. The ends of the tube 5 are closed by two end pieces 8 and 9, which fit into the ends of the 65 tube 5 and are there held by the machine screws 10. The end pieces 8 and 9 are respectively provided with renewable bushings 11 and 12, the bushing 11 having a through-bearing, and the bushing 12 a 70 socket bearing to support a rotary valve later to be described. The tube 5, end pieces 8 and 9, and bushings 11 and 12 form what may be called the discharge valve casing, and this is held in the over-hanging end of 75 the jig-tank by battens 13, 14 and 15, tight joints being made at all points by oakum or other packing 16. Consequently no flow can occur from the tank through the aperture 4 save through the ports 6 and 7.

Free flow through ports 6 and 7 is obstructed by means of a pocketed rotary valve consisting of a hub portion 17 having radial vanes, as shown, to which are adjustably held by bolts 18 the feet or guard plates 19, 80 which are moved outward to compensate for wear. It is to be noted that the space between any two radial vanes must register successively and never simultaneously with the apertures 6 and 7, and that the feet or guard plates 19 blank off a portion of said apertures. Consequently the rotary valve, by its close fit in the tube 5, precludes any free outflow of water from the jig, while the guard plates prevent the entrance of any 85 particles large enough to clog the valve and prevent its rotation. This last result arises partly from the fact of restriction of the entrance aperture and partly from the fact that the feet 19 because of their rearward 90 projection with reference to the rotation of the valve, preserve sufficient unfilled space within the valve pocket to receive the large particles until the valve pocket is fully open, so that such particles readily enter. This 95 feature of the addition of rearwardly projecting feet makes possible the use in jigs for handling coarse material of a close fitting or sealing valve of the rotary type. The valve is rotated through the usual multiple pawls 100 110

20 and ratchet 21, which latter is mounted on a stub shaft 22. This shaft 22 enters through a packing gland 23 and is provided with a squared end 24 engaging a corresponding socket 25 in the valve hub 17 (see Fig. 2).

The heavy material to be discharged from the jig gradually passes from the jig screen 26, down an inclined sluice 27 to the valve. 10 The lighter materials flow off over the discharge plate 28, as is well understood in the art. The line of demarcation between the strata passing out by the overflow and those discharged by the valve may be determined 15 by a vertical adjustment of the plate 29 depending from the inner side of the overflow 28. A secondary plate 30, which also is vertically adjustable, prevents a too rapid flow to the discharge valve; or differently stated, 20 it causes the material to feed to the valve in a thin layer rather than to form a heavy bed over the valve which would cause clogging. In order to vent the air entering the 25 jig through the valve, and otherwise trapped beneath the plate 28, we make use of a vent pipe 31 which may extend upward above the plate 28, as shown, though obviously other arrangements may be made.

From a consideration of the drawing the 30 operation of the device will readily be understood. The heavier material will flow down the inclined plate 27, the depth of flow being determined by the adjustment of carrier 30. The inclination of the top surface of the material flowing beyond plate 30 35 is largely dependent on the angle of repose of the material handled, and the plate is so adjusted that the material will flow into the pocket of the valve in a relatively thin layer. 40 The rearwardly extending foot restricts the opening to this pocket in the valve and by overhanging a portion of the pocket it prevents the complete filling thereof, by preserving an unfilled space immediately under 45 the overhanging foot. Then as the valve continues to rotate and the pocket tends to move out of register with the entrance opening 6 in the valve casing, the material falls away from the opening 6, so that there is nothing 50 to obstruct the rotation of the valve. Thus the free action of the valve is secured by the conjoint action of the barrier 30 and the rotary valve with rearwardly extending feet. The specific proportions and adjustment will 55 vary somewhat according to the characteristics of the material handled.

Incidental advantages are the possibility of readily renewing worn parts and simplicity and cheapness of construction, but the 60 possibility of eliminating the watertight boot heretofore generally used is the feature of greatest value.

Having thus described the invention, what we claim is:—

85 1. The combination with a jig including

the usual tank, screen and overflow for the lighter materials, of a discharge mechanism for the heavier materials comprising a cylindrical valve chamber having lateral ports for the passage of such material; a vaned 70 valve member, rotatably mounted in said chamber, adapted to make close contact with the inner walls thereof, and having rearwardly extending guard plates at the vane extremities; and means for rotating the 75 valve member.

2. The combination with a jig including the usual tank, screen and overflow for the lighter materials, of a discharge mechanism for the heavier materials comprising a cylindrical valve chamber having lateral ports for the passage of such material; a vaned 80 valve member, rotatably mounted in said chamber, adapted to make close contact with the inner walls thereof, and having rearwardly extending guard plates at the vane extremities; a barrier plate adapted to restrict the depth of solid material flowing to 85 said discharge mechanism; and means for rotating said valve member.

3. The combination with a jig including a tank, screen, and overflow for the lighter materials, of a discharge mechanism for the heavier materials comprising a cylindrical valve chamber having lateral ports; a vaned 90 valve member rotatably mounted in said chamber; rearwardly extending guard plates radially adjustable on said vanes to make sealing contact with the walls of said chamber; and means for rotating the valve 95 member.

4. The combination with a jig including a tank, screen, and overflow for the lighter materials, of a discharge mechanism for the heavier materials comprising a cylindrical 105 valve chamber having lateral ports; a vaned valve member rotatably mounted in said chamber; rearwardly extending guard plates radially adjustable on said vanes to make sealing contact with the walls of said chamber; a barrier plate to restrict the depth of 110 flow of solid material to said discharge mechanism; and means for rotating the valve member.

5. The combination with a jig including a 115 tank, screen, and an overflow for the lighter materials, of a discharge mechanism for the heavier materials comprising a cylindrical valve chamber having lateral ports; a pocketed valve rotating therein, the openings to said pockets being restricted in area sufficiently to prevent complete filling of said pockets in the normal operation of the valve; and means for rotating said valve.

6. The combination with a jig including a 125 tank, screen, and an overflow for the lighter materials, of a discharge mechanism for the heavier materials comprising a cylindrical valve chamber having lateral ports; a pocketed valve rotating therein, the openings to 130

5 said pockets being restricted in area sufficiently to prevent complete filling of said pockets in the normal operation of the valve; a barrier to restrict the depth of solid material flowing to said valve; and means for rotating said valve.

7. The combination with a jig including a tank, screen, and an overflow for the lighter materials, of a discharge mechanism for the 10 heavier materials comprising dividing means adapted to define the line of division between the strata of lighter and heavier materials; an inclined sluice for the heavier material leading from said dividing means; 15 a barrier mounted above said sluice beyond said dividing means and adapted to restrict the depth of solid material flowing down said sluice; a pocketed valve adapted to receive material from said sluice beyond said 20 barrier and to discharge it from the jig; and means for operating said valve.

8. The combination with a jig including a tank, screen and overflow for the lighter

25 materials, of a discharge mechanism for the heavier materials, comprising a cylindrical valve chamber having lateral ports; a vaned valve member adapted to rotate in said chamber in sealing contact with the walls thereof and having rearwardly extending guard plates adjacent the vane extremities; 30 means for adjusting said valve member to compensate for wear between it and said chamber; and means for rotating the valve member.

In testimony whereof we have signed our 35 names to this specification each in the presence of two subscribing witnesses.
